CONTROL APPARATUS

Harry A. Rolnick, Philadelphia, Pa., assignor to
The Brown Instrument Company, Philadelphia,
Pa., a corporation of Pennsylvania

Application February 1, 1938, Serial No. 188,030

6 Claims. (Cl. 236—82)

The general object of the present invention is to provide improved control apparatus of the so-called "air controller" type, adapted to effect a control action automatically dependent upon a variable control quantity, by varying a control pressure in predetermined accordance with changes in the control quantity. A more specific object of the invention is to provide such control apparatus with improved means through which an initial fluid pressure change, resulting directly from a change in the control quantity, effects an automatic adjustment of the control apparatus and thereby produces another and related change in the control pressure.

A still more specific object of the present invention is to retain certain characteristic advantages of, and to obtain certain advantages not obtainable with, air controllers of a type and form now in extensive commercial use, comprising a so-called flapper valve, adjusted in direct response to a change in a control temperature, pressure or other control quantity, to variably throttle the discharge through a bleed nozzle, and thereby vary the pressure in said nozzle, and comprising means through which said change in the nozzle pressure results in an immediate or quickly effected second adjustment of the flapper valve partially neutralizing the first mentioned adjustment thereof, and a slowly effected third adjustment of the flapper valve in the same direction as the original adjustment. Said second adjustment or its effect is commonly referred to as a follow-up adjustment or effect, and said third adjustment or effect is commonly referred to as a compensating or reset adjustment or effect.

The present invention is characterized, in particular, by the means through which a reset or compensating effect is obtained with means mechanically separate from and independent of the flapper valve, and neither adjusting nor modifying the adjustment of the flapper valve, and which may be more rugged and less delicate in adjustment and action than the means now in common use for obtaining reset or compensating effects by flapper valve adjustments. My improved air controller preferably includes means for effecting follow-up adjustments of the flapper valve, which are mechanically separate and distinct from the means provided to secure the reset or compensating effects, and which may be omitted from the controller without requiring any modification in the construction of, or interfering with the operative effect of the last mentioned means.

The various features of novelty which characterize my invention are pointed out with particularity in the claims annexed to and forming a part of this specification. For a better understanding of the invention, however, its advantages and specific objects attained with its use, reference should be had to the accompanying

drawing and descriptive matter in which I have illustrated and described preferred embodiments of the invention.

Of the drawing:

5 Fig. 1 is a diagrammatic representation of a furnace control system including one embodiment of the present invention; and

10 Fig. 2 is a diagrammatic view illustrating a modification of a portion of the apparatus shown in Fig. 1.

15 In the particular form of embodiment and use of the invention illustrated diagrammatically in Fig. 1, A represents an oil heater or other industrial heater or furnace, supplied with fluid fuel through a pipe A', at a rate regulated by a fluid pressure motor valve A², which is adjusted to vary the fuel supply rate in accordance with changes in a fluid control pressure, the latter being transmitted to the motor pressure chamber A³ of the valve A², and being varied automatically by variations in the furnace temperature to which a fluid pressure thermometer bulb b is exposed. In the particular arrangement shown and hereinafter described in detail, an increase or decrease in the temperature of the bulb results in an increase or decrease, respectively, in the pressure transmitted to the valve chamber A³, and in a decrease or increase, respectively, in the rate at which fuel is supplied to the furnace.

20 30 The pressure in the bulb b is transmitted to a pressure gauge element shown as comprising a Bourdon tube helix B, and a shaft B' given a clockwise or counterclockwise adjustment by an increase or decrease, respectively, in the pressure transmitted from the bulb b to the helix B. The shaft B' carries a pen arm B², adapted to make a temperature record on a scaled record chart disc B³. The shaft B' also carries an arm B⁴ through

25 35 40 which the angular adjustment of the shaft B' resulting from changes in the temperature of the bulb b, adjusts the control apparatus and thereby varies the control pressure in the chamber A³.

45 50 The arm B⁴ operates through a link B⁵ connecting said arm to one arm of a floating bell crank lever C, having an adjustable fulcrum pivot C', and the second arm of which carries a pin C² engaging one side of a flapper valve D. The latter has a pivotal support D', and is spring biased to turn toward a cooperating bleed nozzle E, so that the discharge orifice in the latter is subjected to an increased or decreased throttling effect by a movement of the pin C² to the right or to the left. The fulcrum pivot C' of the lever C, is carried by a lever F pivoted at F' to a chambered element G. The latter is normally stationary, but as hereinafter described, may be bodily adjusted for a calibration purpose. The member G also carries the nozzle E, and the pivotal support D' for the flapper valve D.

55 60 65 70 The element G encloses a pressure space G' having a flexible wall portion. The latter is in

the form of a bellows H having one end closed by an end wall H' movable relative to the member G, and having its other end open and rigidly connected to the member G. As shown, the bellows H is subjected internally to the pressure of the atmosphere, and externally to the pressure in the chamber or space G' so that an increase in the last mentioned pressure causes the bellows to contract, until the increase in the bellows contracting force is balanced by a spring force which opposes the contraction of the bellows and increases as the latter is contracted. As diagrammatically shown, said spring force is wholly due to the resiliency of the bellows. The movable end wall H' of the bellows H, is connected by a link H² extending axially through the bellows to the lever F at a point between the pivots C' and F'. The bellows H is a follow-up device, operating as hereinafter described, in response to a pressure change in the chamber G' to effect a follow-up adjustment of the flapper D which quickly follows and partially neutralizes each flapper adjustment effected by angular adjustment of the lever C.

The nozzle E is connected to a source of air under pressure, shown as pipe I, by a branch pipe I' which includes a throttling or flow restricting device I², the latter preferably including a needle valve or analogous element I³, which may be manually adjusted to vary the flow restricting effect of the device I². The pressure in the nozzle E and in the portion of the piping connecting the latter to the outlet of the device I², thus depends upon the throttling effect of the flapper valve D, and is increased or decreased by an adjustment of the latter toward or away from the nozzle E. The nozzle pressure is transmitted by the pipe branch I⁴ to a pressure responsive device J in the form of an expansible bellows to which the pipe I⁴ opens. The bellows has one end secured to a support J' and has its other end closed and movable, and pivotally connected to one end of a lever element J². The bellows J resiliently opposes its expansion and has a definite length for each value of its internal pressure.

The expansion or contraction of the bellows J in response to an increase or decrease in the nozzle pressure, effects an increase or decrease, respectively, in the delivery pressure of a valve K. The latter, as shown, comprises an inlet chamber K' connected to a source of air under pressure which may be, and as shown is the pipe I, and which communicates through a port K² with the delivery pressure chamber K³ of the valve. The chamber K³ bleeds air to the atmosphere at a rate depending on the adjustment of the valve member K⁵, which is adapted on its adjustment to simultaneously exert an increased throttling effect on one, and a decreased throttling effect on the other of the two ports K² and K⁴.

The pressure in the chamber K³ is aptly termed the control valve pressure, because it is transmitted through piping K⁶ to the motor pressure chamber A³ of the valve A², to control the adjustment of the latter. It is also transmitted through the piping K⁶ to the chamber G', whereby changes in said pressure produce the previously mentioned follow-up adjustment actions of the bellows H.

In the arrangement shown in Fig. 1, the elongation of the bellows J, resulting from an increase in the throttling effect of the flapper valve D, results in a down movement of the valve member K⁵, increasing the throttling effect on

the port K⁴, and decreasing the throttling effect on the port K², each of the two throttling effect variations contributing to a resultant increase in the pressure in the chamber K³. As shown, the valve member K⁵ is connected to and adjusted by a lever L, which has a stationary fulcrum pivot L', and is biased by a spring L² for movement in the direction to move the valve member K⁵ upward.

- 10 The elongation of the bellows J gives the lever L a counterclockwise adjustment through adjustable thrust transmitting means shown as comprising parts M, N and J³. The part J³ is carried by the lever J² and extends into engagement with the part N, which is an arm generally parallel to the levers J² and L, and the part M is a thrust pin interposed between the levers N and L. Advantageously, for a reason hereinafter stated, the part J³ is adapted to be adjustably clamped to the lever J² in different positions along the length of the latter. The arm N is mounted on a pivot support N' adjacent the end of the lever L to which the valve member K⁵ is connected, so that the pin M is located between the pivotal supports N' and L' for the arm N and lever L. In consequence, the leverage with which the lever J² acts on the valve member K⁵, may be varied by adjusting the pin M longitudinally of the lever L and arm N. To facilitate such adjustment, the pin M is carried by one end of a link M' which is pivotally connected at its other end to an arm M² pivoted to turn about a stationary shaft M³ and adapted to be held, as by friction, in any angular position into which it may be adjusted.

Mounted on the support J' alongside the bellows J, is a second pressure responsive device O, which, as shown, is a bellows similar to the bellows J. The bellows O has one end fixed to the support J' and has its other end closed and movable, and pivotally connected to the second end of the lever J². The control valve pressure is transmitted to the interior of the bellows O from the piping K⁶, through a pipe O' including a flow restricting device O² preferably comprising a manually adjustable needle valve or analogous adjustable throttling element O³.

The parts are shown in Fig. 1, in the relative positions which they assume for some particular stable operating condition, in which the temperature of the bulb b remains constant at a predetermined normal value. On a decrease in the temperature of the bulb b, the parts B⁵, C², J and K⁵ are given movements in the direction of the arrows respectively adjacent those parts, and on an increase in the temperature of the bulb, the said parts are given movements in directions opposite those indicated by the adjacent arrows. The movement of the pin C² in the direction of the adjacent arrow, occurring as a result of a decrease in the temperature of the bulb b, moves the flapper D away from the nozzle E, and thereby immediately reduces the pressure in the chamber of the bellows J, which is in relatively free, or unrestricted, communication with the nozzle E.

The resultant up adjustment of the valve member K⁵ increases the throttling of the port K² and reduces the throttling of the port K⁴, and each of those throttling changes contributes to the resultant reduction in the control valve pressure in the chamber K³. The reduction in that pressure, transmitted by the piping K⁶ to the valve chamber A³, results in an opening adjustment of the valve A², thereby increasing the fuel

supply to the furnace A, and tending to raise the furnace temperature to which the bulb b responds, to its normal value. The decrease in the control valve pressure, transmitted by the piping K⁶ to the chamber G', results in an immediate elongation of the bellows H and consequent immediate return movement of the pin C² to the right. The follow-up adjustment of the flapper valve D thereby effected partially neutralizes the reduction in the nozzle pressure produced by the initial angular adjustment of the lever C, and is ordinarily advantageous for reasons well known to those skilled in the art.

The net effect of the above described initial and follow-up adjustments of the flapper valve D, resulting from the described decrease in temperature of the bulb b, is a reduction in the pressure in the bellows J and a corresponding reduction in the control pressure maintained in the chambers K³, A³, and G' and piping K⁶. This reduction in the control pressure is transmitted to the pressure responsive device O at a slow rate, due to the effect of the flow restricting device O². As the pressure in the bellows O is thus reduced, that bellows contracts, and the valve member K⁵ is given a further adjustment in the same direction as that produced by the previous contraction of the bellows J.

Operations which are the converse of those just described result from an increase in the temperature of the bulb b following a steady operating condition in which the control parts have come into a condition of equilibrium. As those skilled in the art will understand, while the normal and ultimate average effect of an increase or decrease in the temperature of the bulb b is a corresponding quick adjustment of the control pressure in the corrective direction effected by the change in length of the bellows J and a delayed adjustment of the control pressure in the same direction effected through the bellows O, with relatively rapidly alternating increases and decreases in the temperature of the bulb, the bellows O may either slowly contract or slowly expand during a period immediately following either a contraction or an expansion of the bellows J. However, when the resultant of rapidly recurring bulb temperature fluctuations is an increase or decrease, the ultimate resultant effect of the operation of the device O is to augment the effect on the control pressure produced by the ultimate resultant effect of the bellows J. The bellows O thus serves the normal intended purpose of compensating adjustment means, in that it compensates for load changes in the controlled system. Thus in the furnace control system shown in Fig. 1, the bellows O causes the valve A² to be more widely open for a given bulb temperature, during any extended period of operation in which the furnace load is relatively heavy, and the need for fuel correspondingly large, than during an extended period in which the furnace load is relatively light and less fuel is needed.

The apparatus diagrammatically illustrated in Fig. 1 is characterized by its relative simplicity and inherent operative reliability and by the ease with which desirable adjustment may be provided. Thus, as shown, in Fig. 1, the relative effects of the pressure responsive devices J and O on the adjustment of the valve member K⁵ and on the control valve pressure, may be varied by adjusting the thrust part J³ along the length of the lever J². Furthermore, with any given adjustment of the part J³, the throttling range of the control apparatus, or range of variation in the

nozzle pressure transmitted to the bellows J, which is required to vary the control valve pressure to the extent required for the adjustment of the valve A² between its wide open and fully closed positions, depends upon the adjustment of the thrust pin M longitudinally of the lever L and arm N. An adjustment of the pin M to the right increases, and its adjustment to the left decreases the magnitude of the change in the control valve pressure produced by a given change in the pressure transmitted from the nozzle E to the bellows J.

The type of apparatus shown in Fig. 1 is advantageously characterized further, by the flexibility which it permits in the design and assembly of apparatus operating in accordance with the principles of the invention. Thus for example, the size and inherent elasticity of each of the bellows devices J and O employed, may be determined with special reference to the particular conditions of use, and in the actual production of a commercial instrument, the latter may be assembled for use under particular operating conditions, by suitable selection from stock including interchangeably usable bellows parts of different dimensions and resiliency. The valve K which serves the purposes of a booster valve may be of a form, and have a range of adjustment of its valve member K⁵ large enough to insure reliable operation, with a relatively simple and inexpensive construction.

Usually, control apparatus intended for the general purposes for which the apparatus of Fig. 1 is adapted, desirably includes means for varying the control setting point, or value of the control quantity which the apparatus tends to maintain. One known arrangement for the purpose is illustrated in Fig. 1, and comprises means for bodily adjusting the member G about a supporting pivot G', so as to thereby change the relative positions of the flapper D and nozzle E, with a given position of the arm B⁴. To effect such adjustment, the member G is shown as formed with a gear segment G¹⁰ engaged by a manually rotatable worm P supported in the bearings P'. As shown, the rotation of the worm P also angularly adjusts a gear segment Q pivoted at Q' and connected by a link Q² to an index Q³ pivoted on, or coaxially with, the shaft B', and adapted to indicate on the chart B³ the temperature of the bulb b which the apparatus tends to maintain.

In the modification shown in Fig. 2, the pipe O' with its flow restricting device O², does not connect the bellows O to the pipe K⁶, but to the interior of a bellows S located within a pressure chamber R and having a closed and movable end wall, so that the bellows S is caused to contract and elongate by an increase or decrease, respectively, in the control valve pressure, which is transmitted to the interior of the chamber R by a branch from the pipe K⁶. The flow through that branch pipe is not restricted, so that changes in the control valve pressures are transmitted without delay to the chamber R. The bellows O and S and connecting pipe O' of Fig. 2, are preferably filled with an incompressible liquid, so that as the bellows contract and elongate, the bellows O correspondingly elongates and contracts, respectively. The arrangement shown in Fig. 2 has the advantage over that shown in Fig. 1 in that it is practically possible to more readily and accurately regulate the flow through a restricted passage of a liquid than of an elastic fluid as air.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. In air control apparatus, the combination with a pressure responsive device, of means comprising an adjustable valve mechanism and means responsive to variations in a control quantity for adjusting said valve mechanism, for subjecting said device to a pressure varying promptly and in predetermined relation with variations in said control quantity, means including a second adjustable valve mechanism for maintaining a control pressure dependent on the adjustment of said second valve mechanism, a second means to adjust said first valve mechanism, a non-restricted flow passage through which changes in said controlled pressure operate said second adjusting means to adjust said first valve mechanism in a direction opposite to the movement imparted to it by the control responsive means, a second pressure responsive device, means including a restricted flow passage through which changes in said control pressure are slowly transmitted to said second responsive device, and lever mechanism separate from said first mentioned valve mechanism actuated jointly by the two pressure responsive devices to directly adjust said second valve mechanism in prompt response to a change in the pressure to which the first mentioned responsive device is subjected, and to effect a retarded adjustment of said second valve mechanism on a change in said control pressure in a direction augmenting the last mentioned change.

2. Apparatus as specified in claim 1, in which said second pressure responsive element is an expandable container and in which the means for transmitting the control pressure changes to said container comprise a second expandable container, a restricted flow passage connecting the interiors of the two containers, liquid filling said containers and passage, and means subjecting said second container externally to said control pressure.

3. Apparatus as specified in claim 1, including means for varying the relative adjustment effects of the two pressure responsive devices on said second valve mechanism, resulting from a change in the control quantity.

4. Apparatus as specified in claim 1, including means for varying the magnitude of the control pressure change produced by a given change in the pressure to which the first mentioned device of claim 1 is subjected.

5. In air control apparatus, the combination with a pressure responsive device, of means comprising an adjustable valve mechanism and means responsive to variations in a control quantity for adjusting said valve mechanism, for subjecting said device to a pressure varying promptly and in predetermined relation with variations in said control quantity, means including a second adjustable valve mechanism for main-

taining a control pressure dependent on the adjustment of said second valve mechanism, a second means to adjust said first valve mechanism, a non-restricted flow passage through which changes in said control pressure operate said second adjusting means to adjust said first valve mechanism in a direction opposite to the movement imparted to it by the control responsive means, a second pressure responsive device, means including a restricted flow passage through which changes in said control pressure are slowly transmitted to said second responsive device, and means cooperating with the two pressure responsive devices to adjust said second valve mechanism in prompt response to a change in pressure to which the first mentioned responsive device is subjected, and to effect a retarded adjustment of said second valve mechanism on a change in said control pressure in a direction augmenting the last mentioned change, each of the pressure responsive devices being an expandable container subjected internally to the corresponding pressure and both containers acting on said second valve mechanism through an equalizing connection, whereby the contraction and expansion of either container adjusts said valve mechanism in the same direction as the contraction or expansion of the other container.

6. In air control apparatus, the combination with a pressure responsive device, of means comprising an adjustable valve mechanism and means responsive to variations in a control quantity for adjusting said valve mechanism, for subjecting said device to a pressure varying promptly and in predetermined relation with variations in said control quantity, means including a second adjustable valve mechanism for maintaining a control pressure dependent on the adjustment of said second valve mechanism, a second means to adjust said first valve mechanism, a non-restricted flow passage through which changes in said control pressure operate said second adjusting means to adjust said first valve mechanism in a direction opposite to the movement imparted to it by the control responsive means, a second pressure responsive device, means including a restricted flow passage through which changes in said control pressure are slowly transmitted to said second responsive device, and means cooperating with the two pressure responsive devices to adjust said second valve mechanism in prompt response to a change in the pressure to which the first mentioned responsive device is subjected, and to effect a retarded adjustment of said second valve mechanism on a change in said control pressure in a direction augmenting the last mentioned change, each of the two pressure responsive devices being bellows elements located alongside of one another and each having one end stationary and the other end movable and connected to the corresponding end of a floating lever, means operatively engaging said lever intermediate its ends through which the expansion of either bellows produces an adjustment of the second valve mechanism in one direction, and contraction produces an adjustment on the opposite direction and in which the pressure first mentioned is transmitted to the interior of one of said bellows and the control pressure is transmitted to the interior of the second bellows.
